DESIGN FOR A CHAIR

James R. Staudt and Rochelle E. Goddard, Fort Worth, Tex.; said Staudt assignor to said Goddard

Application October 28, 1946, Serial No. 134,339

Term of patent 14 years

(Cl. D15—1)

To all whom it may concern:

Be it known that we, James R. Staudt and Rochelle E. Goddard, citizens of the United States of America, residing at Fort Worth, in the county of Tarrant and State of Texas, have invented a new, original, and ornamental Design for a Chair, of which the following is a specification, reference being had to the accompanying drawing, forming part thereof.

Figure 1 is a side elevational view of a chair, showing our new design.

Figure 2 is a front elevational view thereof, and Figure 3 is a top plan view of our new design.

We claim:

The ornamental design for a chair, substantially as shown.

JAMES R. STAUDT.
ROCHELLE E. GODDARD.
